(57) **CLAIM**

I claim the ornamental design for a handle, as shown and described.

DESCRIPTION

FIG. 1 is a rear view of a handle showing my new design; FIG. 2 is a bottom view of the handle shown in FIG. 1; FIG. 3 is a front view of the handle shown in FIG. 1; FIG. 4 is a left side view of the handle shown in FIG. 1; FIG. 5 is a front, left, top perspective view of the handle shown in FIG. 1;

FIG. 6 is a right side view of the handle shown in FIG. 1; and,

FIG. 7 is a top view of the handle shown in FIG. 1. The broken lines illustrate portions of the handle that form no part of the claimed design.

1 Claim, 7 Drawing Sheets
